(57) **CLAIM**

The ornamental design for an insulated corner block, as shown and described.

DESCRIPTION

FIG. 1 is a perspective view of the insulated corner block showing my new design;

FIG. 2 is a front view thereof;

FIG. 3 is a back view thereof;

FIG. 4 is a left side view thereof;

FIG. 5 is a right side view thereof;

FIG. 6 is a bottom view thereof;

FIG. 7 is a top view thereof;

FIG. 8 is a top view thereof, with the insulated corner block being shown in a condition of use with other blocks; and, FIG. 9 is another top view thereof, with the insulated corner block being used in another condition of use.

The broken lines of FIGS. 8 and 9 depict environmental structures around the insulated corner block and form no part of the claimed invention.
